(57) **CLAIM**

The ornamental design for a candle, as shown and described.

DESCRIPTION

FIG. 1 is a front top perspective view of a candle showing my new design in a first configuration;

FIG. 2 is a left top perspective view thereof;

FIG. 3 is a top view thereof;

FIG. 4 is a bottom view thereof;

FIG. 5 is a front side view thereof;

FIG. 6 is a left side view thereof;

FIG. 7 is a right view thereof; and,

FIG. 8 is a back view thereof.

Those portions of the figures that are presented in broken lines merely illustrate the environment of the design and are not part of the claimed design.
